(57) **ABSTRACT**

A load identification method for reciprocating machinery based on information entropy and envelope features of an axis trajectory of a piston rod. According to the present disclosure, firstly, the position of an axial center is calculated according to a triangle similarity theorem to obtain an axial center distribution; secondly, features are extracted from the axial center distribution of the piston rod by means of an improved envelope method for discrete points as well as an information entropy evaluation method; thirdly, a dimensionality reduction is carried out on the features by means of manifold learning to form a set of sensitive features of the load; and finally, a neural network is trained to obtain a load identification classifier to fulfill automatic identification on the operating load of the reciprocating machinery. The advantages of the present disclosure are verified by means of actual data of a piston rod of a reciprocating compressor.

LOAD IDENTIFICATION METHOD FOR RECIPROCATING MACHINERY BASED ON INFORMATION ENTROPY AND ENVELOPE FEATURES OF AXIS TRAJECTORY OF PISTON ROD

CROSS-REFERENCE TO RELATED APPLICATIONS

This application claims priority to Chinese Application Serial No. 201911079879.2, filed on Nov. 7, 2019, the content of which is incorporated herein by reference in its entirety.

TECHNICAL FIELD

The present disclosure relates to a load identification method for reciprocating machinery.

BACKGROUND

A load variation typically refers to changes of dynamic characteristics of mechanical structures, which lead to an influence on fault features of vibration signals, displacement signals, and the like. It has always been difficult to implement fault monitoring and diagnosis in variable load conditions. Piston rods as movable key parts of reciprocating machinery are prone to causing loosening, cracking, or even breaking to fasteners. There have been many research reports on the fault monitoring and diagnosis of the reciprocating machinery as well as research reports on axis trajectories of the piston rods. For example, an acoustic emission technology is adopted to perform on-line monitoring on the piston rods to pre-warn accidents. A method for fault diagnosis and analysis based on the axis trajectories of the piston rods in the X direction and Y direction can fulfill an early warning of potential faults on the piston rods and piston assemblies of the reciprocating machinery. A harmonic wavelet is used to extract vibration energy, natural frequencies, areas of trajectory envelopes, and other features based on the axis trajectories of the piston rods for fault diagnosis.

At present, there are few reports on the extraction of motion features of the piston rods in the variable load conditions. When a change to the load conditions and faults occur simultaneously, it is necessary to determine why the load conditions of the piston rods change, and the features of influences on loads and the faults should be deeply researched to prevent the faults from being falsely determined. Accordingly, it can be valuable to research transient motion features of the piston rods in the variable load conditions. In view of this, the present disclosure provides a method for extracting information entropy and envelope features of a discrete point distribution contour based on an axis trajectory of a piston rod, which extracts the features of the axis trajectory of the piston rod in different load conditions and establishes a set of sensitive feature parameters of a load as well as a load identification model by means of training.

SUMMARY

The objective of the present disclosure is to provide a simple and effective load identification method for reciprocating machinery, which extracts information entropy and envelope features based on data of an axis trajectory to establish a set of sensitive features of the load for load

2

identification on reciprocating machinery. The present disclosure has simple calculation, high adaptability, high accuracy in identification, and the like.

The objective of the present disclosure is fulfilled through the following technical solution: firstly, the position of an axial center is calculated based on settlement data and deflection data of a piston rod; secondly, an envelope feature of an axial center distribution is extracted by means of an improved envelope method for a discrete point distribution contour, then an information entropy feature of the axial center distribution is calculated, and an initial feature set is formed by the envelope feature and the information entropy feature; and thirdly, sensitive features of the load are extracted from the initial feature set by means of manifold learning to form a set of the sensitive features of the load, and a neural network is trained by means of the set of the sensitive features of the load to obtain an identification classifier.

A load identification method for reciprocating machinery based on information entropy and envelope features of an axis trajectory of a piston rod includes the following steps:

step 1. setting different load conditions $\text{Load} = \{0, d, 2d, 3d, \dots, wd\}$, $w=0, 1, 2, \dots$, where d represents a load gradient, and the number of the load conditions is $(w+1)$ in total; respectively acquiring, by an on-line monitoring system of reciprocating machinery, an original deflection displacement $X_m = \{x_1, x_2, x_3, \dots, y_m\}$ and original settlement displacement $Y_m = \{y_1, y_2, y_3, \dots, y_m\}$ of a piston rod in a corresponding load condition through an eddy current displacement sensor (deflection sensor) in a horizontal direction and an eddy current displacement sensor (settlement sensor) in a vertical direction to obtain an original data set $XY_n = \{(X_m, Y_m)_1^T, (X_m, Y_m)_2^T, \dots, (X_m, Y_m)_n^T\}^T$, where m represents the number of sampling points, and n represents the number of data groups;

step 2. removing average values of an original signal X_m and an original signal Y_m by means of formula (1) to obtain $X'_m = \{x'_1, x'_2, x'_3, \dots, x'_m\}$ and $Y'_m = \{y'_1, y'_2, y'_3, \dots, y'_m\}$, where the original data set is turned to $XY'_n = \{(X'_m, Y'_m)_1^T, (X'_m, Y'_m)_2^T, \dots, (X'_m, Y'_m)_n^T\}^T$

$$F'_m(j) = F_m(i) - \frac{1}{m} \sum_{i=1}^m F_m(i) \quad (1)$$

$$i, j = 1, 2, \dots, m$$

where, in formula (1), F_m represents the original deflection or settlement displacement of the piston rod, and F'_m represents the deflection or settlement displacement, obtained after the average values are removed, of the piston rod; and

setting a horizontal direction measured by a deflection sensor as an X-axis and a vertical direction measured by a settlement sensor as a Y-axis to build a plane-rectangular coordinate system, where if a position of an axial center of the piston rod at an initial time is denoted by $O_0(a_0, b_0)$, the position of the axial center of the piston rod at another time is denoted by $O_m(a_m, b_m)$, and a radius of the piston rod is denoted by R , a point of intersection between a circumference of the piston rod and the X-axis at this time is $J_X(R+x'_m, 0)$, and a point of intersection between the circumference of the piston rod and the Y-axis at the time is $J_Y(0, R+y'_m)$; setting an included angle between the X-axis and a line connecting the point O_m to the point J_X as θ and an included angle between a line connecting the point O_m to

the point J_Y and a straight line, parallel to the X-axis, on which the point O_m is located as φ to derive formula (2) and formula (3) according to a triangle similarity theorem; and solving, by means of formula (2) in combination with formula (3), the position $O_m(a_m, b_m)$ of the axial center of the piston rod at different times to form an axial center distribution set $O=\{O_1(a_1, b_1), O_2(a_2, b_2), O_3(a_3, b_3), \dots, O_m(a_m, b_m)\}$

$$\begin{cases} \frac{R + X'_m(j) + a_m}{X'_m(j)} = \frac{R}{X'_m(j)/\cos\theta} \\ \theta = \arctan \frac{b_m}{R + X'_m(j) + a_m} \end{cases} \quad (2)$$

$$\begin{cases} \frac{R + Y'_m(j) - b_m}{Y'_m(j)} = \frac{R}{Y'_m(j)/\sin\varphi} \\ \varphi = \arctan \frac{R + Y'_m(j) - b_m}{a_m} \end{cases} \quad (3)$$

where, in formula (2) and formula (3), $j=1, 2, 3, \dots, m$
step 3. calculating an envelope feature B_{ao} of the axial center distribution $O=\{O_1(a_1, b_1), O_2(a_2, b_2), O_3(a_3, b_3), \dots, O_m(a_m, b_m)\}$ by means of an improved envelope method for a discrete point distribution contour, where the improved envelope method for the discrete point distribution contour particularly includes the following steps:

step 3.1. determining, according to the axial center distribution O , four limit points by seeking a minimum point a_l and a maximum point a_r in the horizontal direction X as well as a minimum point b_d and a maximum point b_u in the vertical direction Y, where the four limit points are respectively denoted by $O_l(a_l, b_l)$, $O_r(a_r, b_r)$, $O_d(a_d, b_d)$, $O_u(a_u, b_u)$, an inside of a quadrangle formed by the four limit points is counted as an internal side, and an outside of the quadrangle is counted as an external side;

step 3.2. extracting a convex envelope of an axial center distribution contour at a minimum slope with the foregoing limit points as starting points by anticlockwise traversing all over the positions of the axial center at all times; and

calculating a convex envelope between a limit point O_d and a limit point O_r through a method including the following steps;

(1) setting a line connecting the point O_d to the point O_r as L_1 , where a slope α_1 of the line is expressed as:

$$\alpha_1 = \frac{b_d - b_r}{a_d - a_r} \quad (4)$$

(2) if a set of all common axial center points on an external side of the line L_1 is assumed as $P=\{p_1(a_1, b_1), p_2(a_2, b_2), p_3(a_3, b_3), \dots\}$, calculating a slope $K=\{\beta_1, \beta_2, \beta_3, \dots\}$ of a line connecting the point O_d to any point in P ; if there are multiple points with a same slope, calculating a distance $D=\{dis_1, dis_2, dis_3, \dots\}$ between the corresponding point and the point O_d ; and seeking a point $p'(a_p, b_p)$ in the set P , and enabling p' to meet the following formula:

$$\beta'=\min K, \beta' \leq \alpha_1, \text{ and } dis'=\max D \quad (5)$$

where, in formula (5), β' represents a slope of a line connecting the point p' to the point O_d , and dis' represents a distance between the point p' and the point O_d ; and

the point p' is a convex envelope point;

(3) replacing the point O_d with the convex envelope point p' , setting a line connecting the point p' to the point O_r as L'_1

and a slope of the line L'_1 as α'_1 , and then carrying out a next iteration to seek a new convex envelope point;

(4) repeating step (1), step (2), and step (3); and when a distance between the new convex envelope point and the point O_r is 0, stopping the iteration to obtain a convex envelope $B'_{dr}=\{p'_1, p'_2, p'_3, \dots\}$ of an axial center distribution contour between the limit point O_d and the limit point O_r , and

calculating a convex envelope B'_{ru} between the limit point O_r and a limit point O_u , a convex envelope B'_{ul} between the limit point O_u and a limit point O_l , and a convex envelope B'_{ld} between the limit point O_l and the limit point O_d to obtain a set $B_{tu}=\{O_d, B'_{dr}, O_r, B'_{ru}, O_u, B'_{ul}, O_l, B'_{ld}\}$ of all convex envelope points in the axial center distribution;

(5) calculating an area $S1$ of the convex envelope of the axial center distribution contour by means of formula (6) below:

$$S1 = \frac{1}{2} \sum_{e=1}^{c1} (a_{pe} * b_{p(e+1)} - a_{p(e+1)} * b_{pe}) \quad (6)$$

where, in formula (6), $c1$ represents the number of the convex envelope points;

step 3.3. calculating a concave envelope of the axial center distribution according to the convex envelope obtained in step 3.2; and

calculating a concave envelope between the limit point O_d and the limit point O_r by successively anticlockwise carrying out the following calculation on two continuous convex envelope points $p'_1(a_{p1}, b_{p1})$ and $p'_2(a_{p2}, b_{p2})$ in the convex envelope $B'_{dr}=\{p'_1, p'_2, p'_3, \dots\}$:

(1) setting a line connecting the point $p'_1(a_{p1}, b_{p1})$ to the point $p'_2(a_{p2}, b_{p2})$ as L_2 , where a slope α_2 of the line L' is expressed as:

$$\alpha_2 = \frac{b_{p2} - b_{p1}}{a_{p2} - a_{p1}} \quad (7)$$

(2) if a set of all common axial center points on an internal side of the line L_2 is assumed as $Q=\{q_1(a_1, b_1), q_2(a_2, b_2), q_3(a_3, b_3), \dots\}$, calculating a slope $K'=\{\beta'_1, \beta'_2, \beta'_3, \dots\}$ of a line connecting the point p'_1 to any point in Q ; if there are multiple points with a same slope, calculating a distance $D'=\{dis'_1, dis'_2, dis'_3, \dots\}$ between the corresponding point and the point p'_1 ; and seeking a point $q'(a_q, b_q)$ in the set Q , and enabling q' to meet the following formula:

$$\beta''=\min K', \beta'' \geq \alpha_2, \text{ and } dis''=\max D' \quad (8)$$

where, in formula (8), β'' represents a slope of a line connecting the point q' to the point p'_1 , and dis'' represents a distance between the point q' and the point p'_1 ; and

the point q' is a concave envelope point;

(3) replacing the point p'_2 with the concave envelope point q' , setting a line connecting the point p'_1 to the point q' as L'_2 and a slope of the line L'_2 as α_2 , and then carrying out a next iteration to seek a new concave envelope point;

(4) repeating step (1), step (2), and step (3); and when a distance between the new concave envelope point and the point p'_1 is not greater than M , stopping the iteration to obtain a concave envelope $B''_{dr}=\{q'_1, q'_2, q'_3, \dots\}$ of the axial center distribution contour between the limit point O_d and the limit point O_r ; where,

an initial value of M indicates an average distance between two adjacent axial center points, and M is calculated by means of formula (9) in combination with formula (10):

$$M = \frac{2M'}{m(m-1)} \quad (9)$$

$$M' = \sum_{i=2}^m \left| \sqrt{(a_1 - a_i)^2 + (b_1 - b_i)^2} \right| + \sum_{i=3}^m \left| \sqrt{(a_2 - a_i)^2 + (b_1 - b_i)^2} \right| + \dots + \sum_{i=m}^m \left| \sqrt{(a_{m-1} - a_i)^2 + (b_{m-1} - b_i)^2} \right| \quad (10)$$

calculating a concave envelope B''_{ru} between the limit point O_r and a limit point O_u , a concave envelope B''_{ul} between the limit point O_u and a limit point O_l , and a concave envelope B''_{ld} between the limit point O_l and the limit point O_d to obtain a set $B_{ao} = \{O_d, B''_{dr}, O_r, B''_{ru}, O_u, B''_{ul}, B''_{ld}\}$ of all concave envelope points in the axial center distribution;

(5) calculating an area S2 of the concave envelope of the axial center distribution contour by means of formula (11) below:

$$S2 = \frac{1}{2} \sum_{g=1}^{c2} (a_{qg} * b_{q(g+1)} - a_{q(g+1)} * b_{qg}) \quad (11)$$

where, in formula (11), c2 represents the number of the concave envelope points;

step 3.4. determining whether or not the set B_{ao} , obtained in step 3.3, of the concave envelope points is the envelope feature of the axial center distribution of the piston rod;

(1) calculating a relative error E of S2 and S1 by means of formula (12) till E is less than or equal to 5%, where the set B_{ao} , obtained in step 3.3, of the concave envelope points is the envelope feature of the axial center distribution of the piston rod after the calculation is stopped;

$$E = \frac{|S2 - S1|}{S1} \times 100\%; \quad (12)$$

and

(2) in a case where the distance M is reduced by 50% when E is greater than 5%, replacing S1 with S2, repeating step 3.3 to obtain a new set B'_{ao} of the concave envelope points as well as an area S2' of the concave envelope; and repeatedly calculating a relative error E' of S2' and S2 by means of formula (13) till E' is less than or equal to 5%, where the iteration is stopped at this moment, and the set B'_{ao} obtained in Step 3.3 is the envelope feature of the axial center distribution of the piston rod during the last iteration;

$$E' = \frac{|S2' - S2|}{S2} \times 100\% \quad (13)$$

step 4. calculating an information entropy feature of the axial center distribution O: calculating, by means of formula (14), arithmetic square roots of coordinates of all the points in the axial center distribution O to obtain a set $S_m = \{s_1, s_2, \dots, s_3, \dots, s_m\}$, and then calculating the information entropy feature Sh of the axial center distribution O by means of formula (15), where an initial feature set $T = \{B_{ao}, Sh\}$ is formed by the information entropy feature Sh and the envelope feature;

$s_3, \dots, s_m\}$, and then calculating the information entropy feature Sh of the axial center distribution O by means of formula (15), where an initial feature set $T = \{B_{ao}, Sh\}$ is formed by the information entropy feature Sh and the envelope feature;

$$S_m(i') = \left| \sqrt{a_{k'}^2 + b_{k'}^2} \right|, k, i' = 1, 2, \dots, m \quad (14)$$

$$Sh = - \sum_{i'=1}^m \left(\frac{|S_m(i')|}{\sum_{i'=1}^m |S_m(i')|} * \log_2 \left(\frac{|S_m(i')|}{\sum_{i'=1}^m |S_m(i')|} \right) \right) \quad (15)$$

15 step 5. carrying out, by means of t-distributed stochastic neighbor embedding (T-SNE), an unsupervised dimensionality reduction on the initial feature set to extract sensitive features of a load; and assuming that the initial feature set T includes 1*Col-dimensional features, given perplexity is 30, and a given learning rate is 1e-5, setting a label as Labels = {0, 1, 2, ..., w}, and then inputting the initial feature set T to a T-SNE algorithm for the unsupervised dimensionality reduction in the (w+1) load conditions to obtain a set $T' = \{t_1, t_2\}$ of the sensitive features of a 1*2-dimensional load; and

20 step 6. firstly, sorting data acquired by the on-line monitoring system in the (w+1) load conditions to form a training set and a test set; secondly, processing the data in the training set and the test set through the above steps to obtain a final training set Train_T' and a final test set Test_T'; and thirdly, setting, according to different reciprocating machinery, the number of neurons of a back-propagation (BP) neural network as 20-30, a learning rate as 0.0005-0.001, training accuracy as 0.0001-0.0005, and maximum iterations as 25 70-100, then inputting the data set Train_T' to the BP neural network for training to obtain a classifier capable of distinguishing the (w+1) load conditions of the reciprocating machinery, and testing the classifier of the BP neural network by means of the test set Test_T'.

BRIEF DESCRIPTION OF DRAWINGS

FIG. 1 is a flow chart of a method of the present disclosure;

FIG. 2 is a schematic diagram showing the position of an axial center;

FIG. 3 shows a settlement waveform and deflection waveform of a piston rod of a reciprocating compressor;

FIG. 4 shows an axial center distribution;

FIG. 5 shows an envelope feature calculated by means of an improved method;

FIG. 6 shows sensitive features of a load; and

FIG. 7 shows an envelope feature calculated by means of a traditional method.

DETAILED DESCRIPTION

For the sake of better understanding of the technical solution of the present disclosure, the specific embodiments of the present disclosure are further expounded below with reference to data of a piston rod of a reciprocating compressor and the accompanying drawings.

Step 1. Acquire, by an on-line monitoring system of a reciprocating compressor, deflection data X_m and settlement data Y_m of a piston rod in load conditions of 0%, 20%, 50%, 60%, 70%, 80%, 90%, and 100% to form an original data set $XY_n = \{(X_m, Y_m)_1^T, (X_m, Y_m)_2^T, \dots, (X_m, Y_m)_n^T\}^T$, where n

represents the number of data groups and is equal to 500, waveforms are shown in FIG. 3, original data of eight loads fall into a training set and a test set, and 400 data groups in the training set and 100 data groups in the test set are set for each load;

Step 2. Remove average values of an original signal X_m and an original signal Y_m to obtain $X'_m = \{x'_1, x'_2, x'_3, \dots, x'_m\}$ and $Y'_m = \{y'_1, y'_2, y'_3, \dots, y'_m\}$, and solve, according to a triangle similarity theorem, the position of an axial center of the piston rod to obtain an axial center distribution set $O = \{O_1(a_1, b_1), O_2(a_2, b_2), O_3(a_3, b_3), \dots, O_m(a_m, b_m)\}$, where an axial center distribution is shown in FIG. 4;

Step 3. Calculate an envelope feature B_{ao} of the axial center distribution O by means of an improved envelope method for a discrete point distribution contour, as shown in FIG. 5;

Step 4. Calculate an information entropy feature Sh of the axial center distribution, where an initial feature set $T = \{B_{ao}, Sh\}$ is formed by the information entropy feature and the envelope feature;

Step 5. In a case where given perplexity is 30 and a given learning rate is 1e-5, extract sensitive features of the loads from T by means of manifold learning to form a set $T' = \{t_1, t_2\}$ of the sensitive features of the loads, as shown in FIG. 6; and

Step 6. Process the data from the training set and the test set through Step 2 to Step 5 to respectively obtain a final training feature set $Train\_T'$ and a final test feature set $Test\_T'$; and set the number of neurons of a back-propagation (BP) neural network as 30, a learning rate as 0.001, training accuracy as 0.0001, and maximum iterations as 100, input the data set $Train\_T'$ to the BP neural network for training to obtain a classifier capable of distinguishing 8 load conditions of the reciprocating compressor, test the classifier of the BP neural network by means of the test set $Test\_T'$, and compare the improved envelope method with a traditional envelope method for extracting the envelope feature (as shown in FIG. 7); where, a result is shown in Table 1.

TABLE 1

What is claimed is:

1. A load identification method for reciprocating machinery based on information entropy and envelope features of an axis trajectory of a piston rod, comprising the following steps:

step 1. setting different load conditions $Load = \{0, d, 2d, 3d, \dots, wd\}$, $w=0, 1, 2, \dots$, wherein d represents a load gradient, and the number of the load conditions is $(w+1)$ in total; respectively acquiring, by an on-line monitoring system of reciprocating machinery, an original deflection displacement $X_m = \{x_1, x_2, x_3, \dots, x_m\}$ and original settlement displacement $Y_m = \{Y_1, Y_2, Y_3, \dots, y_m\}$ of a piston rod in a corresponding load condition through an eddy current displacement sensor

in a horizontal direction and an eddy current displacement sensor in a vertical direction to obtain an original data set

$XY_n = \{(X_m, Y_m)_1^T, (X_m, Y_m)_2^T, \dots, (X_m, Y_m)_n^T\}^T$, wherein m represents the number of sampling points, and n represents the number of data groups;

step 2. removing average values of an original signal X_m in and an original signal Y_m by means of formula (1) to obtain $X'_m = \{x'_1, x'_2, x'_3, \dots, x'_m\}$ and $Y'_m = \{y'_1, y'_2, y'_3, \dots, y'_m\}$, wherein the original data set is turned to $XY'_n = \{(X'_m, Y'_m)_1^T, (X'_m, Y'_m)_2^T, \dots, (X'_m, Y'_m)_n^T\}^T$

$$F'_m(j) = F_m(j) - \frac{1}{m} \sum_{i=1}^m F_m(i) \quad (1)$$

$$i, j = 1, 2, \dots, m$$

wherein, in formula (1), F_m represents the original deflection or settlement displacement of the piston rod, and F'_m represents the deflection or settlement displacement, obtained after the average values are removed, of the piston rod; and setting a horizontal direction measured by a deflection sensor as an X-axis and a vertical direction measured by a settlement sensor as a Y-axis to build a plane-rectangular coordinate system, wherein if a position of an axial center of the piston rod at an initial time is denoted by $O_0(a_0, b_0)$, the position of the axial center of the piston rod at another time is denoted by $O_m(a_m, b_m)$, and a radius of the piston rod is denoted by R , a point of intersection between a circumference of the piston rod and the X-axis at this time is $J_x(R+x'_m, 0)$, and a point of intersection between the circumference of the piston rod and the Y-axis at the time is $J_y(0, R+y'_m)$; setting an included angle between the X-axis and a line connecting the point O_m to the point J_x as θ and an included angle between a line connecting the point O_m to the point J_y and a straight line, parallel to the X-axis, on which the point O_m is located as φ to derive formula (2) and formula (3) according to a triangle similarity theorem; and solving, by means of formula (2) in combination with formula (3), the position $O_m(a_m, b_m)$ of the axial center of the piston rod at different times to form an axial center distribution set

$$O = \{O_1(a_1, b_1), O_2(a_2, b_2), O_3(a_3, b_3), \dots, O_m(a_m, b_m)\} \quad (2)$$

$$\begin{cases} \frac{R + X'_m(j) + a_m}{X'_m(j)} = \frac{R}{X'_m(j)/\cos\theta} \\ \theta = \arctan \frac{b_m}{R + X'_m(j) + a_m} \end{cases}$$

$$\begin{cases} \frac{R + Y'_m(j) - b_m}{Y'_m(j)} = \frac{R}{Y'_m(j)/\sin\varphi} \\ \varphi = \arctan \frac{R + Y'_m(j) - b_m}{a_m} \end{cases} \quad (3)$$

wherein, in formula (2) and formula (3), $j=1, 2, 3, \dots, m$ step 3. calculating an envelope feature B_{ao} of the axial center distribution $O = \{O_1(a_1, b_1), O_2(a_2, b_2), \dots, O_3(a_3, b_3), \dots, O_m(a_m, b_m)\}$ by means of an improved envelope method for a discrete point distribution contour, wherein the improved envelope method for the discrete point distribution contour particularly comprises the following steps:

step 3.1. determining, according to the axial center distribution O , four limit points by seeking a minimum point a_l and a maximum point a_r in the horizontal direction X as well as a minimum point b_d and a maximum point b_u in the vertical direction Y , wherein the four limit points are respectively denoted by $O_d(a_l, b_d), O_r(a_r, b_r), O_d(a_d, b_d), O_u(a_u, b_u)$, an inside of a quadrangle formed by the four limit points is counted as an internal side, and an outside of the quadrangle is counted as an external side;

step 3.2. extracting a convex envelope of an axial center distribution contour at a minimum slope with the foregoing limit points as starting points by anticlockwise traversing all over the positions of the axial center at all times; and

calculating a convex envelope between a limit point O_d and a limit point O_r through a method comprising the following steps:

(1) setting a line connecting the point O_d to the point O_r as L_1 , wherein a slope α_1 of the line is expressed as:

$$\alpha_1 = \frac{b_d - b_r}{a_d - a_r} \quad (4)$$

(2) if a set of all common axial center points on an external side of the line L_1 is assumed as $P=\{p_1(a_1, b_1), p_2(a_2, b_2), p_3(a_3, b_3), \dots\}$, calculating a slope $K=\{\beta_1, \beta_2, \beta_3, \dots\}$ of a line connecting the point O_d to any point in P ; if there are multiple points with a same slope, calculating a distance $D=\{dis_1, dis_2, dis_3, \dots\}$ between the corresponding point and the point O_d ; and seeking a point $p'(a_p, b_p)$ in the set P , and enabling p' to meet the following formula:

$$\beta' = \min K, \beta' \leq \alpha_1, \text{ and } dis' = \max D \quad (5)$$

wherein, in formula (5), β' represents a slope of a line connecting the point p' to the point O_d , and dis' represents a distance between the point p' and the point O_d ; and the point p' is a convex envelope point;

(3) replacing the point O_d with the convex envelope point p' , setting a line connecting the point p' to the point O_r as L'_1 and a slope of the line L'_1 as α'_1 , and then carrying out a next iteration to seek a new convex envelope point;

(4) repeating step (1), step (2), and step (3); and when a distance between the new convex envelope point and the point O_r as 0, stopping the iteration to obtain a convex envelope $B'_{dr}=\{p'_1, p'_2, p'_3, \dots\}$ of an axial center distribution contour between the limit point O_d and the limit point O_r ; and

calculating a convex envelope B'_{ru} between the limit point O_r and a limit point O_u , a convex envelope B'_{ul} between the limit point O_u and a limit point O_b , and a convex envelope B'_{ld} between the limit point O_l and the limit point O_d to obtain a set $B_{ru}=\{O_d, B'_{dr}, O_r, B'_{ru}, O_u, B'_{ul}, O_b, B'_{ld}\}$ of all convex envelope points in the axial center distribution;

(5) calculating an area $S1$ of the convex envelope of the axial center distribution contour by means of formula (6) below:

$$S1 = \frac{1}{2} \sum_{e=1}^{c1} (a_{pe} * b_{p(e+1)} - a_{p(e+1)} * b_{pe}) \quad (6)$$

wherein, in formula (6), $c1$ represents the number of the convex envelope points;

step 3.3. calculating a concave envelope of the axial center distribution according to the convex envelope obtained in step 3.2; and

calculating a concave envelope between the limit point O_d and the limit point O_r by successively anticlockwise carrying out the following calculation on two continuous convex envelope points $p'_1(a_{p1}, b_{p1})$ and $p'_2(a_{p2}, b_{p2})$ in the convex envelopes $B'_{dr}=\{p'_1, p'_2, p'_3, \dots\}$:

(1) setting a line connecting the point $p'_1(a_{p1}, b_{p1})$ to the point $p'_2(a_{p2}, b_{p2})$ as L_2 , wherein a slope α_2 of the line L' is expressed as:

$$\alpha_2 = \frac{b_{p2} - b_{p1}}{a_{p2} - a_{p1}} \quad (7)$$

(2) if a set of all common axial center points on an internal side of the line L_2 is assumed as $Q=\{q_1(a_1, b_1), q_2(a_2, b_2), q_3(a_3, b_3), \dots\}$, calculating a slope $K'=\{\beta'_1, \beta'_2, \beta'_3, \dots\}$ of a line connecting the point p'_1 to any point in Q ; if there are multiple points with a same slope, calculating a distance $D'=\{dis'_1, dis'_2, dis'_3, \dots\}$ between the corresponding point and the point p'_1 ; and seeking a point $q'(a_q, b_q)$ in the set Q , and enabling q' to meet the following formula:

$$\beta'' = \min K', \beta'' \geq \alpha_2, \text{ and } dis'' = \max D' \quad (8)$$

wherein, in formula (8), β'' represents a slope of a line connecting the point q' to the point p'_1 , and dis'' represents a distance between the point q' and the point p'_1 ; and

the point q' is a concave envelope point;

(3) replacing the point p'_2 with the concave envelope point q' , setting a line connecting the point p'_1 to the point q' as L'_2 and a slope of the line L'_2 as α_2 , and then carrying out a next iteration to seek a new concave envelope point;

(4) repeating step (1), step (2), and step (3); and when a distance between the new concave envelope point and the point p'_1 is not greater than M , stopping the iteration to obtain a concave envelope $B''_{dr}=\{q'_1, q'_2, q'_3, \dots\}$ of the axial center distribution contour between the limit point O_d and the limit point O_r ; wherein, an initial value of M indicates an average distance between two adjacent axial center points, and M is calculated by means of formula (9) in combination with formula (10):

$$M = \frac{2M'}{m(m-1)} \quad (9)$$

$$55 \quad M' = \sum_{i=2}^m \left| \sqrt{(a_1 - a_i)^2 + (b_1 - b_i)^2} \right| + \sum_{i=3}^m \left| \sqrt{(a_2 - a_i)^2 + (b_1 - b_i)^2} \right| + \dots + \sum_{i=m}^m \left| \sqrt{(a_{m-1} - a_i)^2 + (b_{m-1} - b_i)^2} \right| \quad (10)$$

calculating a concave envelope B''_{ru} between the limit point O_r and a limit point O_u , a concave envelope B''_{ul} between the limit point O_u and a limit point O_b , and a concave envelope B''_{ld} between the limit point O_l and the limit point O_d to obtain a set $B_{ao}=\{O_d, B''_{dr}, O_r, B''_{ru}, O_u, B''_{ul}, O_b, B''_{ld}\}$ of all concave envelope points in the axial center distribution;

11

(5) calculating an area S2 of the concave envelope of the axial center distribution contour by means of formula (11) below:

$$S2 = \frac{1}{2} \sum_{g=1}^{c2} (a_{qg} * b_{q(g+1)} - a_{q(g+1)} * b_{qg}) \quad (11)$$

5

wherein, in formula (11), c2 represents the number of the concave envelope points; 10

step 3.4. determining whether or not the set B_{ao} , obtained in step 3.3, of the concave envelope points is the envelope feature of the axial center distribution of the piston rod; 15

(1) calculating a relative error E of S2 and S1 by means of formula (12) till E is less than or equal to 5%, wherein the set B_{ao} , obtained in step 3.3, of the concave envelope points is the envelope feature of the axial center distribution of the piston rod after the calculation is stopped; 20

$$E = \frac{|S2 - S1|}{S1} \times 100%; \quad (12) \quad 25$$

and

(2) in a case where the distance M is reduced by 50% when E is greater than 5%, replacing S1 with S2, 30 repeating step 3.3 to obtain a new set B'_{ao} of the concave envelope points as well as an area $S2'$ of the concave envelope; and repeatedly calculating a relative error E' of $S2'$ and $S2$ by means of formula (13) till E' is less than or equal to 5%, wherein the iteration is 35 stopped at this moment, and the set B'_{ao} obtained in Step 3.3 is the envelope feature of the axial center distribution of the piston rod during the last iteration; 40

$$E' = \frac{|S2' - S2|}{S2} \times 100%; \quad (13)$$

step 4. calculating an information entropy feature of the axial center distribution O: calculating, by means of

12

formula (14), arithmetic square roots of coordinates of all the points in the axial center distribution O to obtain a set $S_m = \{s_1, s_2, s_3, s_m\}$ of the arithmetic square roots, and then calculating the information entropy feature Sh of the axial center distribution O by means of formula (15), wherein an initial feature set $T = \{B_{ao}, Sh\}$ is formed by the information entropy feature Sh and the envelope feature;

$$S_m(i') = \left| \sqrt{a_k^2 + b_k^2} \right|, k, i' = 1, 2, \dots, m \quad (14)$$

$$Sh = - \sum_{i'=1}^m \left(\frac{|S_m(i')|}{\sum_{i'=1}^m |S_m(i')|} * \log_2 \left(\frac{|S_m(i')|}{\sum_{i'=1}^m |S_m(i')|} \right) \right) \quad (15)$$

step 5. carrying out, by means of t-distributed stochastic neighbor embedding (T-SNE), an unsupervised dimensionality reduction on the initial feature set to extract sensitive features of a load; and assuming that the initial feature set T includes 1*Col-dimensional features, given perplexity is 30, and a given learning rate is 1e-5, setting a label as Labels = {0,1,2, ..., w}, and then inputting the initial feature set T to a T-SNE algorithm for the unsupervised dimensionality reduction in the (w+1) load conditions to obtain a set $T' = \{t_1, t_2\}$ of the sensitive features of a 1*2-dimensional load; and

step 6. firstly, sorting data acquired by the on-line monitoring system in the (w+1) load conditions to form a training set and a test set; secondly, processing the data in the training set and the test set through the above steps to obtain a final training set Train_T' and a final test set Test_T'; and thirdly, setting, according to different reciprocating machinery, the number of neurons of a back-propagation (BP) neural network as 20-30, a learning rate as 0.0005-0.001, training accuracy as 0.0001-0.0005, and maximum iterations as 70-100, then inputting the data set Train_T' to the BP neural network for training to obtain a classifier capable of distinguishing the (w+1) load conditions of the reciprocating machinery, and testing the classifier of the BP neural network by means of the test set Test_T'.
